CLAIM

The ornamental design for a function selector and cursor controller, as shown and described.

DESCRIPTION

FIG. 1 is a perspective view of a function selector and cursor controller showing my new design.

FIG. 2 is a top plan view;

FIG. 3 is a front elevational view;

FIG. 4 is a right side elevational view; and

FIG. 5 is a rear elevational view.

The broken line showing of a power cord in FIG. 1 is for illustrative purposes only and forms no part of the claimed design.

FIG. 1.

FIG. 3.

FIG. 4.

FIG. 5.
